By his attorney,

Inventor:

James A. Craig,

J. W. Richards.

UNITED STATES PATENT OFFICE.

JAMES A. CRAIG, OF PEEKSKILL, NEW YORK, ASSIGNOR OF TWO-THIRDS TO ROBINA MORTIMER SINCLAIR AND WILLIAM EDGAR SAMPSON, BOTH OF TORONTO, ONTARIO, CANADA.

TAPERED-FACE GRINDING PLATE.

Application filed June 1, 1923. Serial No. 642,812.

This invention relates to grinding mills of the type embodying oppositely rotating shafts carrying opposing grinding disks or plates, and more particularly to the plates themselves.

One of the objects of the invention is to provide such a plate which has both faces arranged for grinding, and which is reversible and adapted to be easily attached to a standard head or holder.

Another object of the invention is to provide such a plate having either both or one of its grinding faces formed to provide, with an opposing plate, a space therebetween which decreases outwardly from the center. This construction facilitates grinding, as all material, of whatever hardness or size (the size of course being within the limits of the space between the center of the plates) is drawn into contact with the grinding faces, and is gradually and continuously diminished in size as it passes between the converging faces of the plates to the outlet at the outer edges thereof. Because of this even, continuous receiving of the material to be ground, a consistent mixture of a combination of different materials of varying sizes and hardness, such as oats, wheat, and corn, may be produced.

Still another object of the invention is to provide such a plate which may be easily balanced after it has been made and tempered.

Other objects of the invention will appear as the description proceeds; and while herein details of the invention are described, the invention is not limited to these, since many and various changes may be made without departing from the scope of the invention as claimed.

In the accompanying drawing, showing by way of example one of many possible embodiments of the invention, Fig. 1 is a view of one face of the plate.

Fig. 2 is a sectional elevation on line 2—2 of Fig. 1.

Fig. 3 is a face view, enlarged, of a segment of a plate.

Fig. 4 is a segmental sectional view on line 3—3 of Fig. 3, showing a plate holding the bolt hole.

Fig. 5 is a sectional view on line 4—4, Fig. 3, showing in addition, in dotted lines, the grinding face of an opposing plate.

In the embodiment shown there is provided a holder H of the usual construction, having a circular recess therein to receive the grinder plate A, which plate is provided with ribs, generally denoted by B. The plate A with the ribs B is a single piece of drop forged steel, tempered.

The ribs B comprise radial ribs b joined together by circular ribs d, thereby forming depressions or pockets 10. The ribs B are provided with faces 12 ground to provide cutting edges 15 around said faces, but where the ribs B join the plate A to form the depressions 10, the corners are rounded, which facilitates bringing the material into contact with said cutting edges 15 by giving it, in conjunction with the opposite plate, a rolling motion out of the depressions against the cutting edges of the ribs.

The surfaces of the ribs B are ground to form an angle, as 16, Fig. 5, to a plane 20, thereby providing, with an opposite plate D, shown in dotted lines in Fig. 5, an outwardly decreasing space 22 between said converging plates A and D.

For attaching the plate A to the head H, there are provided, near the inner and outer edges on both sides of the plate, preferably, but not necessarily, in staggered relation, registering rectangular bosses 30, the faces 31 of which lie in the outer face planes 85 of the plate; the edges of the faces 31 also being cutting edges. Through the bosses 30 and plate A there is provided a tapped bolt hole 40, as shown in Fig. 4, and when the plate is placed in the holder, which is provided with holes registering with holes 40, bolts 45 are passed through holder and screwed into holes 40, thereby securing the plate firmly in the holder H. The faces of bosses 30 being in the same plane wear 95 equally and when the plate is reversed present a flat bearing surface against the holder H.

As the plate wears the ends of bolts 46 wear down with the bosses 30, and when the plate is reversed the bolt heads will exactly fit and rigidly hold the plate in position, even though the ends of the bolts 46 have been worn down so that their faces are lower than the boss faces 31.

Holes or recesses 48 are provided in the outer periphery of the plate so that after the plate is made and tempered, it may be

properly balanced by filling in said holes with any suitable metal the required amount.

What I claim is:—

1. The combination with a grinder plate head having a circular recess, of the reversible grinding disk having tapering grinding faces and disposed in said recess, bosses on one side of said disk having their faces in the same plane, bosses on the other side 10 of said disk having their faces in the same plane and being arranged opposite said first bosses, each pair of opposed bosses having tapped bolt holes extending entirely through the disk, there being bolt holes tapped in 15 said head to register with the bolt holes in said disk, and bolts extending through said head and disk to secure said disk in place with the heads of said bolts disposed adjacent said grinder plate head, the ends of 20 said bolts being disposed adjacent to the grinding face so that the grinding face and the ends of the bolts will be subjected to the same degree of wear.
2. A reversible grinding disk having 25 tapering grinding faces; bosses on one side of said disk having their faces in the same plane; bosses on the other face of said plate having their faces in the same plane and being arranged opposite said first bosses; 30 said bosses on each side being adapted to

provide a plane surface when said plate is reversed, there being bolt holes tapped in said bosses, and bolts disposed therein for securing the disk in place with the ends of the bolts adjacent to the grinding faces.

35

3. A grinding mill, comprising a rotatable head; a reversible grinding disk having tapering grinding faces; bosses on one side of said disk registering with bosses on the other side of the disk, the faces of the 40 bosses on each side lying in the outer planes of the grinding faces; said bosses and plate having tapped bolt holes therethrough; bolts passing through said head into said tapped holes; and there being recesses in the edge 45 of said disk, means in said recesses for balancing said disk after completion.

4. The combination with a grinder plate head, having a circular recess, of reversible grinding disks, having tapering grinding 50 faces on each side thereof and disposed in the recess, a plurality of bosses on each side of the disk, the faces of the bosses on the same side being in the same plane, means in said bosses for attaching the grinding disk 55 to said plate head, said bosses being adapted to wear evenly throughout, whereby to allow for reversal of the disk.

JAMES A. CRAIG.
